UNITED STATES PATENT OFFICE.

HARRY C. CANSLER, OF KNOXVILLE, TENNESSEE.

DESIGN FOR A SEAT.

42,184.

Specification for Design.

Patented Feb. 20, 1912.

Application filed November 14, 1911. Serial No. 660,286. Term of patent 7 years.

To all whom it may concern:

Be it known that I, HARRY C. CANSLER, a citizen of the United States, residing at Knoxville, in the county of Knox and State of Tennessee, have invented a new, original, and ornamental Design for Seats, of which the following is a specification, reference being had to the accompanying drawing, forming part thereof.

The figure is a perspective view of a seat, showing my new design.

I claim:

The ornamental design for a seat, as shown.

HARRY C. CANSLER.

Witnesses:

CHARLES W. CANSLER,
W. F. YARDLEY.
